Ernest L. Du Pree, 60 Sutton Place S., New York, N.Y.

Filed Sept. 20, 1965, Ser. No. 87,077

Term of patent 14 years

(Cl. D58—8)

FIGURE 1 is a front elevational view of a combined decanter and closure therefor embodying my new design; I claim:

I claim:

The ornamental design for a combined decanter and closure therefor, as shown.
